UNITED STATES PATENT OFFICE.

HAZAELE WEST, OF WASHINGTON, DISTRICT OF COLUMBIA.

PAPER GUIDE FOR TYPEWRITERS.

Application filed July 28, 1923. Serial No. 654,448.

To all whom it may concern:

Be it known that I, HAZAELE WEST, a citizen of the United States, residing at Washington, in the District of Columbia, have invented certain new and useful Improvements in Paper Guides for Typewriters; and I do hereby declare the following to be a full, clear, and exact description of the invention, such as will enable others skilled in the art to which it appertains to make and use the same.

The present invention relates to improvements in paper guides for typewriters and has for an object to insure the proper feeding and the proper contact of the paper upon the platen.

In present models of certain standard typing machines, the design and construction of the overhead feed rolls (where such exist) are not such as to properly and effectively fulfill the purpose for which they were intended. With the present construction it is practically impossible to write to the bottom of the sheet without one or both sides of the sheet creeping up in the course of a line, thus making the line spacing irregular and unsightly and eliminating two to four lines of writing space at the bottom of the page.

It is another object of the invention to eliminate the present difficulties by the application of direct yieldable pressure to the over head feed rolls whereby the sheet or sheets may be held in substantially perfect contact with the platen until the entire sheet has been typed down to the very bottom to the end that every line may be evenly and perfectly spaced.

With the over head feed rolls at present used on the Underwood and similar typewriters, a very small amount of pressure is developed upon the sheet of paper on the platen, the pressure being usually insufficient even to hold the rolls in contact with the platen actually leaving a space equal to several thicknesses of paper between the roll and platen.

The rolls are therefore ineffective for the purpose for which they are intended and imperfections in the type alinement and the line spacing result.

A further object of the invention resides in providing relatively inexpensive devices in the nature of attachments which are so designed and constructed as to be capable of substitution for the present forms of over

head feed rolls, taking advantage of the same mounting as now employed but having the further construction and advantage of yieldable direct pressure whereby the feed rolls will at all times remain in firm contact with the platen or with the paper thereon.

With the foregoing and other objects in view the invention consists in the construction, combinations and arrangement of parts hereinafter described and more particularly pointed out in the appended claims.

In the drawings wherein like symbols refer to like or corresponding parts throughout the several views.

Figure 1 is a top plan view showing portions of a typewriter carriage and platen with the invention applied thereto.

Figure 2 is an enlarged fragmentary portion of the platen and showing one of the devices.

Figure 3 is an end view of the platen and associated parts showing the feed rolls in operative and disengaged positions.

Figure 4 is a cross section taken through the same with the feed rolls in engaged position.

Figure 5 is a fragmentary side view showing a modified form of fastening, and

Figure 6 is a transverse section taken on the line 6—6 in Figure 5.

Referring more particularly to the drawings 7 designates generally the typewriter carriage frame and 8 the platen mounted therein.

In accordance with the present construction the carriage frame supports a transverse bar 9 rearwardly of the platen 8 and slightly above the same or at about the same height as the periphery of the platen. This bar in the present Underwood construction forms a support for the arms which carry the guide fingers bearing upon the paper and intended to hold it against the platen.

In the present construction furthermore light springs are associated with the rod 9 and with the arms and these light springs are depended upon entirely to produce the necessary pressure obtaining between the guide fingers and the paper upon the platen. This has been found ineffective in practice and the guide fingers do not in actual practice possess any positive tension whatsoever, particularly after the typewriter has been in use for a short period of time. As a con-

sequence the present fingers perform substantially no function and their result is lost.

I utilize in my construction this rear transverse bar 9 and likewise the arms 10 of the present construction. These arms 10 are also pivoted upon the bar so that they may swing upwardly out of the way as indicated by the dotted line position in Figure 3.

Upon these old parts are imposed the further construction forming the invention. In accordance with the invention a bar 11 is extended transversely across the carriage in substantial parallelism with the rear rod 9, such bar 11 being carried by and affixed to the inturned end portions 12 of the arms 10. The ends of the bar 11 carry forwardly and downwardly curved pressure fingers 13. The outer free ends of these pressure fingers are engaged by the upper ends of coil springs 14 which bear at their lower ends upon the end portions of a rod 15 extending across normally in front of the platen. The lower ends of the springs may be wound about the rod 15 or otherwise secured thereto and the rod is carried in arms 16 which extend forwardly from the first mentioned arms 10 and are pivoted thereto as indicated at 17.

Now the front rod 15 supports the guide fingers 18 and these guide fingers may be of substantially the general shape given the present form of guide fingers and in addition to the usual guide or pressure rolls 19 carried by such fingers 18, I further provide smaller rolls 20 journaled in the upper and rear portions of the guide fingers and adapted to also bear upon the surface of the platen or the sheets of paper thereon. This rear roll 20 subjects the lower front portion of the guide fingers to a substantial pressure at all times and prevents the paper further prying the guide fingers away from the platen so much so as to cause a permanent gap to be created between these two parts. If this front lower portion of the guide fingers were allowed to unduly spread outwardly and forwardly away from the platen it would catch upon other portions of the apparatus during the traverse of the carriage and will interfere with this carriage movement.

The front rod 15 is provided with a longitudinal peripheral groove 21 adapted to receive a tongue 22 upon each guide finger whereby to avoid any relative turning movement of the guide finger upon the rod, particularly when the rod and connected parts are raised to the dotted line position indicated in Figure 3. If the guide fingers were allowed to swing on the rod when lifted, they would require manual adjustment before being lowered and this would be tedious work for the operator and furthermore consume valuable time. The tongue 22 or other

suitable construction acts to frictionally hold the guide finger where placed and avoids casual longitudinal creeping. The front rod 15 is intended to be substantially non-rotating and it would be held in the arm 16 in such a way as to secure this result.

Now in accordance with the new construction the rear arms 10 may be fixed against sliding movement upon the rear rod 9 but the guide fingers 18 are freely slidable upon the front rod 15 and through this construction the same relative spacing between the two guide fingers is secured according to the width of the sheet to be typed.

Now the construction heretofore described will be found adapted for factory replacement but the rear arms 10 as now manufactured are not perforated so as to readily receive the pivots 17. Consequently in making substitutions in machines already on the market, it would become necessary to perforate the arms 10 to receive the pivots 17. In order to dispense with the necessity for so perforating the arms and to avoid the work incident thereto, I provide the device shown in Figures 5 and 6 which consists of a clip 23 bent substantially U-shaped as indicated in Figure 6 and having a screw 24 passing through the leg thereof which lies against the outside face of the forward arm 16. This screw 24 passes through a perforation in the arm 16 and bears against the imperforate overlapped portion of the rear arm 10. The opposite leg of the clip engages upon the outer wall of the rear arm 10 so that the pressure developed by this last mentioned leg and the screw 24 is adequate to hold the arm 16 upon the arm 10.

The clip 23 may be made of resilient metal or other appropriate material.

It will be appreciated from the foregoing that the use of the springs 14 in the position noted will yield a direct and positive thrust upon the guide rollers 19 and that this pressure will at all times be effective inasmuch as it is direct. The positive and direct pressure devolving on the paper by reason of the arrangement of the guide fingers and the guide rolls enables me to hold the paper firmly and faithfully upon the platen without likelihood of creeping particularly when the lower edge of the paper has passed from engagement with the lower feed rollers at which time it has a tendency to creep locally and particularly with reference to one side more than another in the existing typewriter construction. This has always made it difficult to preserve the alinement of the type and the proper spacing of the lines near the bottom of the page but where direct pressure is afforded such as that provided herein in conjunction with double feed rolls, the paper is held against this creeping movement and the line spacing is preserved down to the

very bottom of the sheet. Moreover according to the invention both guide fingers are mounted uniformly upon the same bar so that both fingers may be lifted by one hand of the operator and both restored to normal position in the same way. The fingers will also occupy the same identical positions when restored due to the fact that they are prevented from turning upon the front 10 rod 15.

It is obvious that various changes and modifications may be made in the details of construction and design of the above specifically described embodiment of this invention without departing from the spirit thereof, such changes and modifications being restricted only by the scope of the following claims.

What is claimed is:—

- 20 1. In a typewriter, a platen, a rod extending above and to the rear of the platen, arms pivotally mounted on said rod, a bar connecting said arms, other arms pivotally carried by the first mentioned arms, a second rod supported in said other arms and extending longitudinally above and in front of said platen, paper guide fingers supported on said second rod, rolls in said guide fingers to space the guide fingers 25 from the platen, and resilient means carried by said bar and bearing directly on said

second rod for forcing the rolls against the platen and paper thereon.

2. In a typewriter, a platen, arms pivotally supported above said platen, a rod carried by the arms, paper guide fingers supported for sliding movement on said rod and being prevented from turning thereon, rolls in said guide fingers for bearing against the platen and paper thereon and 35 for spacing the fingers slightly from said platen or paper, and means for communicating yielding pressure to said rod substantially radially with respect to the platen whereby said rolls will receive a direct pressure against the platen without permitting the fingers to be pressed against the platen. 40

3. In a typewriter, a rear rod, arms pivotally carried by the first 50 mentioned arms, a second rod carried by said other arms, paper guide fingers supported for sliding movement on said second rod and being prevented from turning thereon, pairs of rolls in said guide fingers, 55 curved pressure fingers carried by the first mentioned arms and extending beyond said guide fingers, and resilient means disposed between said pressure fingers and the second rod.

HAZAELE WEST.
